FIG. 4.

J. J. Grove Inventor

UNITED STATES PATENT OFFICE.

JOHN J. GROVE, OF DETROIT, MICHIGAN.

DIESTOCK.

Refiled for abandoned application Serial No. 476,386, filed June 10, 1921. This application filed July 2, 1924. Serial No. 723,846.

This invention relates to improvements in die stocks and more particularly to a single implement for cutting various sizes of standard threads on pipes and bolts.

5 One of the objects of the invention is to provide an implement of this character which will have a plurality of openings of various sizes in accordance with the recognized standard cutting dies so that a single 10 implement may be employed for a workman to cut various sizes of threads.

Other objects of the invention will appear upon consideration of the following detail 15 description and accompanying drawings, wherein:—

Figure 1 is a top plan view of the device constructed in accordance with my invention, Figure 2 is a longitudinal section taken on the line 2—2 of Figure 1,

20 Figure 3 is a bottom plan view showing the die plate, and

Figure 4 is a cross section on the line 4—4 of Fig. 1.

The subject matter of this application is 25 the same as that contained in my abandoned application, filed June 10, 1921, Serial No. 476,386.

Referring to the drawing by numerals, the 30 guide plate 1 and the die plate 2 are of the same general construction with respect to their dimensions and outer configuration and they are adapted to be maintained in spaced relation as shown to advantage in Figs. 2 and 4. Accordingly the guide plate 1 is provided at each end with lugs 4 which are equipped with flanges 5 engaged with the inner surface of the die plate 2. Fastening bolts 6 are passed through the flanges 5 and through the end portions of the die plate to 40 secure the die plate and guide plate in proper superposed relation. Each lug 4 is provided with an opening to receive one end of a handle 7. The handles extend in opposite directions in the manner common to die stocks of this character so that a convenient grip may be obtained to rotate the die stock.

A series of openings of various sizes is provided in the guide plate, these openings being indicated at 9. Flanges are provided

on each opening and are formed by upstanding ribs to form additional guide means for the member extending through the openings when the device is in use.

In alignment with the openings 9 are the 55 openings 10 in the die plate which are somewhat larger in diameter as shown and each opening is provided with radially projecting lugs 11 disposed at 90° with respect to each other and the terminals of the lugs are diametrically spaced apart for a distance equal to the diameter of the openings 9. The openings 9 and 10 correspond in diameter to the 60 standard sizes of dies used for cutting the standard threads on bolts and pipes and it will be obvious that the bolts extended through any one of the openings 9 will be engaged by the cutting dies (not shown) in the openings 10 so that the threading operation may be accomplished by simply imparting the necessary rotary movement by 65 manipulating the handle 7.

In this manner a practically universal cutting tool is provided which will permit any size thread to be cut without the adjustment required when various sizes of dies are to 75 be inserted in the implement now generally employed.

Minor changes may be made in the details of construction without departing from the 80 spirit of the invention or the scope of the claims hereunto appended.

What is claimed is:—

A die stock comprising a plate provided at its intermediate portion with a group of 85 openings, one of said openings being located at the center of the plate and at the center of the group of openings, said plate having upon its side surface a continuous rib completely surrounding each opening of the group and all of the openings of the group, the plate having at its opposite side and at 90 opposite points of its edge aligned lugs, a die plate carried by the lugs, and handles detachably connected with the lugs.

In testimony whereof, I have affixed my 95 signature.

JOHN J. GROVE.
